WELT FOR HOSIERY

Lester D. Wagenhorst, Reading, Pa., assignor to
The Nolde and Horst Company, Reading, Pa.,
a corporation of Pennsylvania

Application October 23, 1943, Serial No. 507,369

6 Claims. (Cl. 66—173)

My invention relates to a well-known type of stocking made by longitudinally folding a suitably knitted flat fabric blank and seaming together its side edges, and more specifically it relates to the usual double thickness welt formed at the top of such stocking by an infolded fabric flap, the present improvements being especially adapted for and particularly applicable to narrow welts made in accordance with my prior Patents No. 2,260,960 of October 28, 1941, and No. 2,286,659 of June 16, 1942.

Such narrow welts, because of present war conditions and the need of conserving materials, are a much preferred construction as reducing the cost of knitting the blanks through a substantial saving of the yarn required to form a stocking; but this saving has been more or less offset by such narrow welt requiring joint seaming together of both side edges of the folded welt involving extra costs for this operation.

It is well known that such seaming, as performed by a usual special sewing machine adapted for this purpose, operates best with least trouble and greatest economy when joining the edges of fabric of single thickness, and, therefore, my present main object is to conserve the yarn saving secured with said narrow welt construction by making a stocking which eliminates from such welts any requirement for double thickness seaming together of both folded fabric edges.

With this primary object in view, my present invention relates to a novel and improved construction of the folded-over welt top of a stocking, the nature and advantages of which will be more fully set forth hereinafter in connection with the accompanying drawing and the novel feature defined in the appended claims.

In the drawing:

Fig. 1 is a longitudinal rear perspective view of a known type of stocking made by seaming together the side edges of a flat fabric blank, and showing a preferred narrow top welt for which my improvements are particularly applicable.

Fig. 2 shows on an enlarged scale a longitudinal front perspective view of the top portion only of the stocking indicated in Fig. 1, and discloses an inside view of the rear meeting and seamed together edges of a welt top made according to a preferred embodiment of my invention.

Fig. 3 is a diagrammatic showing of a flat fabric stocking blank partially knitted to a length for forming my improved welt.

Fig. 4 is a view corresponding to Fig. 3, but showing a later stage in the knitting, with the 55

welt completed and a partial continuation of the fabric blank extending below the welt line junction course.

Fig. 5 is a diagrammatic longitudinal fabric section, taken on the line 5—5 of Fig. 4.

The best known type of stocking for which my improvements are particularly applicable is generally known as "full fashioned," and is commonly made in well-known manner, by knitting a suitable flat fabric blank on a usual straight needle bar knitting machine; forming the welt top during such knitting by folding down a top fabric portion and interknitting its lower edge in a welt junction course; completing knitting of the blank fabric; and finally seaming together the side edges of the blank; all as heretofore well understood, and requiring no further description.

The seaming of the fabric edges, as heretofore made on known special sewing machines adapted for the purpose, readily operated on old wide welts having a deep fold by first uniting the single thickness side edges of the outer portion of said fold and then continuing around the fold bend to unite the single thickness of the inner fold edges of said welt, in a common and recognized manner, economically produced.

It will be readily seen however that such usual seaming of the welt is not possible with the present preferred yarn-saving narrow welt having a shallow depth fold, not separable as in a wide welt for seaming together first the outer and then the inner single-thickness edges of said welt fold. These preferred narrow units require so-called double thickness seaming by necessitating simultaneous uniting of both fold edges at one side of the welt with both side edges at the other side of said welt, and the resultant increase in the cost of this operation.

Fig. 1 represents a usual "full fashioned" stocking having a leg portion 1, a preferred narrow top welt portion 2, and a longitudinal seam 3 extending to the top of the fold line of said welt.

In Fig. 3 I have indicated the knitting of the upper end of the fabric blank for making such narrow welt, and have embodied therein my novel construction for producing my improved welt. As heretofore I lay a first course of loops across the needles 5 and engage them on the hooks of a usual welt bar 6 as more fully described in my aforesaid patents, but for my present purpose, such course is laid across only a medial portion of the row of needles subsequently to be employed to knit the desired fabric width, leaving unengaged needles at each side of said first laid course.

By the use of the usual widening mechanism of such known knitting machine, I gradually bring into knitting action all such originally unengaged side needles to widen the successive courses of knitted loops either in frequent narrow steps or less frequent larger steps, so as to produce the fabric portion 7 with angularly inclined side edges 8 and 9 extending to a first full width course indicated by the dotted line 10. This fabric portion 7 forms the folded over portion of my improved welt, the dotted line 10 indicates the fold line for such top portion, and 11 indicates a full-width knitted continuation of the fabric blank having parallel side edges 12 and 13, containing a number of loop courses equal to the courses in the portion 7, and terminating at a welt junction course indicated by a repetition 5' of the row of needles 5.

The fabric blank thus far knitted as shown in Fig. 3, will produce a preferred embodiment of my improved welt, which is completed as shown in Fig. 4, by folding over the portion 7 on the portion 11 along the dotted line 10, and reengaging the first laid course of loops with the needles in known manner. As shown, however, the first laid course of loops being narrower than the full width of the fabric, only medial needles in said welt junction course will be employed, leaving uncovered parts at each side of the portion 11, between the angularly inclined side edges 8 and 9 of portion 7, and also leaving free the side edges 12 and 13 of portion 11, to form single thickness fabric edges in my improved welt. The edges 8 and 9 of the portion 7 need no attachment to the fabric portion 11 or inclusion with the later added longitudinal seam, as they are sufficiently held by the interknitting of the lower edge of said fold 7 with the main loops forming the welt junction line 5'. With the completion of turning the welt, as above, the remainder of the stocking blank is knitted as heretofore, to be completed by the usual operation of seaming together its side edges.

With my improved welt construction as above fully described, it will be clearly evident that the finishing seaming operation is greatly simplified and cheapened, as only single-thickness fabric edges are required to be united, and the seam may be run to the top of the welt without any difficulty.

This single-thickness of the side edges of the welt may be otherwise accomplished than by the preferred manner above described, as by parallel sides throughout a narrow width of the folded over flap portion of said welt. Also the fold line 10 may be made with usual picot loop stitches to ornamenteally finish the welt fold as heretofore.

From the aforesaid description it will be clearly apparent that my improved construction accomplishes my aforesaid object of simplifying and cheapening the seaming operation, thus saving and increasing the economies secured by the use of all narrow welts. The particular construction described may of course be modified and changed within the scope of my invention as defined in the following claims.

What I claim is:

1. A turned welt for a flat-knitted stocking, comprising an inner welt fold having side edges spaced inwardly from the side edges of said welt outer fold, and a longitudinal seam extending to the folded top of said welt and engaging only the outer fold side edges thereof.

2. A turned welt for a flat-knitted fabric stocking, comprising inner and outer welt folds and a longitudinal seam uniting the side edges of said flat knitted fabric and extending to the upper end of said welt; said inner welt fold having side edges diverging from a junction point adjacent the upper end of said welt and extending therefrom in opposite angular directions from the side edges of the outer welt fold and being spaced free from engagement by said longitudinal seam.

3. A welt top for a flat-knitted fabric stocking, comprising a folded-over top fabric portion having spaced-apart fashioned edges diverging in increasingly progressive steps inwardly from the meeting side edges of the fabric portion on which it is folded, and a longitudinal seam extending to the upper end of said welt and engaging only the single meeting edges of the latter.

4. The method of making a turned-welt top portion in a flat-knitted stocking-forming fabric blank having single thickness seam uniting side edges, which consists in knitting a first course of a less number of loops intermediately disposed lengthwise relative to a later knitted full width course of loops, adding successively knitted courses to said first course and gradually increasing the number of loops in certain added courses by a widening knitting thereof so as to form a down-foldable tapered, top-half portion of the welt having oppositely inclined side edges extending from the ends of said first course to the ends of a full width course forming the folding line for said top portion, adding to said full-width folding line course a succession of knitted full width courses of loops equal in number of courses to the number of courses in said top portion to a welt junction course, folding down said top welt portion and interknitting its first course of loops with an interwidth disposed portion of the loops forming the welt junction course so as to leave single thickness welt side edges extending outwardly beyond the inclined side edges of said folded down top portion, and adding additional knitted courses to said welt junction course to complete the stocking forming blank.

5. A flat-knitted stocking-forming blank having side selavage edges and an integrally knitted turned welt at its upper end, the downwardly-folded inner portion of said welt having selavage edges extending from said welt fold in inwardly inclined spaced relation relative to the selavage edges of the outer fold portion of said turned welt.

6. A stocking formed from a flat-knitted fabric blank having side selavage edges throughout its length, a turned welt at its upper end, and a longitudinal seam uniting said selavage edges, the selavage edges of the inner fold of said welt being spaced inwardly from and free from engagement by said seam uniting the selavage edges of the outer fold of said welt.

LESTER D. WAGENHORST.
